SCAFFOLD CONNECTION

Robert E. Hagan, Youngstown, Ohio

Application October 22, 1949, Serial No. 123,061

3 Claims. (Cl. 304—40)

1

This invention relates to sectional scaffolding of the kind having a plurality of transversely extending separable metal end frames which are assembled in vertical superimposed relation and which are braced longitudinally with separable bracing members, and more particularly to improved and simplified arrangements for securely locking the bracing members to the end frames and for locking the superimposed end frames together, if desired.

It is common practice in sectional scaffolding of the kind mentioned to provide separable brace members extending longitudinally and diagonally of the assembled scaffold frames or bents and to provide quick detachable interconnections between the frames or bents and the braces, and it is the primary object of the present invention to provide an improved arrangement for interconnecting the upstanding frames and the diagonal braces whereby all the operative parts are rugged and durable while being permanently attached to either the frame members or the brace members, whereby the brace members may be more efficient and rugged than those heretofore employed while the interconnection itself is of stronger construction than heretofore employed in sectional scaffold equipment. More specifically, the apparatus of the invention is such that maximum use is made of tubular metal parts and sections which possess maximum strength modulae for given weights of material as is well understood in the structural art.

Another object of the invention is the provision of improved sectional scaffolding wherein the component parts for detachably interconnecting the separable frames and braces are of a rugged, blunt nature so as to withstand very severe conditions of service, whether stored or in use, over a long period of time and wherein such parts are permanently carried by the frames and braces, without any tendency of any part to fall off, whereby the scaffolding may be erected at all times simply by assembling only the frames and braces.

The above and other objects and advantages of the invention will become apparent upon consideration of the following detailed specification and the accompanying drawing wherein there is disclosed a preferred embodiment of the invention.

In the drawing:

Figure 1 is a perspective view of an elementary scaffold assembly made up of one pair of spaced frames or bents and a plurality of longitudinally extending diagonal brace members;

Figure 2 is a perspective view, on an enlarged scale, of the upper end portion of one of the vertically extending posts of one of the frames of Figure 1;

2

Figure 3 is a fragmentary end view of one of the brace members shown in position about to be assembled to an adjacent frame;

Figure 4 is a side elevation of one of the brace members; and

Figures 5 and 6 are top and sectional views, respectively, of one of the locking pins used to connect the braces to the frames.

The scaffolding of the invention is, in accordance with usual practice, assembled of a plurality of longitudinally spaced and vertically superimposed frames or bents, two of which are shown at 10 in Figure 1. Each of the frames 10 comprises a pair of spaced vertically extending tubular posts 11 which are interconnected at their top ends by a tubular strut 12 and at their bottom ends by a tubular strut 13. Interconnecting the struts 12 and 13 is a pair of obliquely disposed bracing struts 14 and 15 and it will be understood that all the parts 11 through 15 are suitably welded together to form a rigid frame. In practice, the horizontal members 12 of the various top frames of the scaffolding structure are utilized to support planking, not shown, to support workmen and materials.

On each side of each vertical post 11 and at both the top and bottom ends thereof there is rigidly secured a pair of spaced and aligned tubular collars 16. In actual practice the collars 16 are secured to the posts 11 by fillet-type of welds so that rigid and permanent connections are effected between the collars and the posts. The collars 16 of each pair are spaced sufficiently to snugly receive between them a tubular fitting 17 which is welded to the ends of the brace members 18. The brace members 18 may be of either tubular or rod construction and as evident from Figure 4 the brace member assemblies 17, 18 are reversible so that only one style of brace member is required in the scaffolding assembly.

To releasably secure the brace member fitting 17 between the two collars 16 of the respective pairs thereof each pair of collars is provided with a retractile pin 19 in the form of a tubular member having a rounded lower or inner end, all as shown in Figure 6. Welded or otherwise suitably secured to the upper or outer end of each of the pins 19 is a flange 20 having a cut-away portion 21 for being received about the periphery of the post 11 whereby the pin 19 may be slidably received in the collar 16 in bridging relation to the two collars of each pair thereof. To complete the assembly, I provide means permanently attached to the post 11 to limit the retraction of the various pins 19 so that these pins will be permanently carried by the respective frames of the scaffolding equipment. In the case of the pins 19 which are at the upper ends of the frames the retraction lim-

iting means is in the form of pins 22 which extend diametrically through suitable apertures formed in the upper end portions of the posts 11 and also through apertures formed in centrally shouldered connecting plugs 23 which project into the top ends of the posts 11 as shown in Figure 2. The means limiting the retraction of the pins 19 at the lower ends of the frames are the pins 24 which extend diametrically through the lower end portions of the posts 11. In actual practice, the pins 22 and 24 are driven into place after the pins 19 are inserted in the collars 16 so that the pins 22 and 24 will stay in place permanently while the pins 19 will have limited retraction but will always be carried on the frames. By referring to Figure 2 it will be obvious that the relative location of the various parts is such that the pins 19 may be retracted sufficiently to enable the fitting 17 of the braces 18 to be inserted between the two collars 16 of the respective pairs of collars.

In assembling scaffolding from the parts above described the frames 10 are superimposed on each other with the lower open ends of the tubular posts 11 fitting over the upwardly projecting nibs of the connecting plugs 23 so as to avoid any side-ways slipping of the vertically aligned frames. For most installations this simple sliding connection is efficient but in case it is desirable to more rigidly lock the frames together the lower end of the extremities of the posts 11 are provided with diametric apertures 25 to register with diametric apertures 26 in the plugs 23 whereby connecting pins, not shown, may be driven through these lined apertures as will be understood. The braces 18 are added to the assembly by retracting the pins 19 to enable the fittings 17 to be received between the two collars 16 of the respective pairs of collars after which the pins 19 are moved downwardly to bridge the collars 16 with the fittings 17 locked therebetween.

As explained above, an important feature of the invention is the manner of connecting the diagonal braces 18 to the upright posts 11 of the scaffold frames and it should now be apparent that I have provided an operative connection for these two parts which accomplishes the objects initially set out. The stubby close-coupled nature of the fittings 17 provide brace members of maximum strength and by positioning the ends of these brace members in close proximity to or in contact with the outer surfaces of the posts 11 a maximum of rigidity is obtained in the assembled scaffolding. Any pushing force exerted by a brace is opposed, not alone by the associated pin 19, but also by the direct contact of the associated fitting 17 with the outer surface of the post 11 and with the inner end surfaces of the adjacent collars 16. Forces of tension are opposed by the pins 19, which in themselves are very efficient because of their large diameters, held in two of the collars 16, each of which is sufficiently secured to the post 11 as explained above. The large diameter of the pins 19 is further advantageous in reducing wear and in minimizing the effects of corrosion and other deteriorating actions. Since it is impossible for the fittings 17 to have any influence on the longitudinal or reTRACTING movement of the pins 19 the latter are effectively held in operative positions by a combination of gravity and friction which simplifies the design and operation of the complete apparatus.

The above specifically described embodiment of the invention should be considered as illustrative only as obviously many changes may be made therein without departing from the spirit or scope of the invention. Reference should therefore be had to the appended claims in determining the scope of the invention.

I claim:

1. In a tubular sectional scaffolding of the type comprising spaced vertically disposed frames having spaced pairs of rigidly connected upstanding posts, diagonal brace members for connecting the top portions of certain of said frames to the bottom portions of certain others of said frames, and detachable means for releasably connecting said brace members to said frames; the improvement in said detachable means comprising spaced vertically aligned pairs of tubular collars rigidly secured to and directly in contact with the outer surface of said posts near both the top and bottom ends thereof, the space between said collars being substantially greater than the internal diameter thereof, vertically aligned elongated tubular fittings of the same cross-section as said collars rigidly secured at each end of said diagonal brace members and adapted to be received between the collars of each pair, said fittings being substantially equal in length to the length of said space, pins slidably received in said collars and adapted to be inserted simultaneously in said collars and fittings to contact said members to said spaced frames, and means limiting the sliding movement of said pins whereby each pin is at all times inserted in a collar and thus held against separation from the adjacent post, the outside diameter of said pins being substantially equal to the inside diameters of said tubular collars and fittings.
2. Apparatus according to claim 1 further characterized in that the means limiting the sliding movement of said pins in one direction comprises wide flanges on the upper ends of said pins adapted to engage and rest on the upper ones of the spaced pairs of collars, said flanges extending radially outward of said collars whereby to be readily grasped and axially withdrawn to release said fittings, and said flanges being recessed on the side thereof adjacent said posts.
3. Apparatus according to claim 2 further characterized in that the means limiting the sliding movement of said pins in the opposite direction comprises retaining pins extending into the sliding paths of travel of said pins whereby to limit the extent of withdrawal of said pins from their respective pairs of collars.
